WINDOW FRAME AND SASH ASSEMBLY

Joseph Sylvan, Berkley, Mich.

Application September 7, 1951, Serial No. 245,510.

10 Claims. (Cl. 189—75)

This invention relates to a window frame and sash assembly adapted to replace the conventional double hung window sashes in a permanent window opening.

An object is to provide a frame formed of relatively light sheet or extruded metal having opposed complementary jamb members exhibiting a pair of upper sash guide channels opening into single opposed complementary lower guide channels similar to the disclosure of my co-pending application Serial No. 245,509.

Another object is to provide a window sash frame that may be inserted within a permanent window opening, the conventional double hung sashes having been removed, between the outer weather stop and the inner trim strip.

Another object is to provide a window frame and sash assembly which may be removably mounted within a permanent window opening in place of conventional double hung sashes and which will be held therein by the usual parts associated with such a permanent window, such as the outer weather stop and the inner trim panel. When said frame is inserted within the permanent window opening it is held therein by said parts without additional securing means.

A meritorious feature of the invention is the provision of opposed jamb members whose lower guide channel inner wall are cut away to permit the insertion or removal of a sash therethrough.

A further object is to provide a frame having opposed jamb faces exhibiting a pair of upper sash guide channels opening into single lower sash guide channels. The inner wall of said lower channels is cut away to permit a sash mounted in said channel to be inclined inwardly of the window opening and held against further inclination by a pair of sash retaining catches swingably mounted on the inner faces of the side rails of the sash and adapted to be swung to engage perforations in the bottom walls of said lower channels.

Another object is to provide a window frame and sash assembly constructed that the sashes may be readily inserted within or removed from the frame, and yet when the sashes are positioned to admit air to the room, it is not possible for one on the outside of the building to raise the sashes or remove them to gain entrance.

Another object is to provide a frame having opposed jamb faces exhibiting a pair of opposed complementary upper sash guide channels opening into single lower opposed sash guide channels which lower channels have their inner walls cut away for substantially their entire length to permit a sash in the channels to be inclined inwardly of the window opening. The meeting rail of said sash when tilted inwardly is adapted to engage the bottom edges of the inner walls of said upper sash guide channels. This construction prevents raising of the sash from outside the window opening.

A meritorious feature of the invention is that when the lower sash is tilted inwardly of the window opening and held there positioned by the sash retaining catches and the engagement of the meeting rail of the sash with the bottom edges of the inner walls of the upper guide channels, a second sash mounted in the upper guide channels may be lowered to bear against the exterior faces of the side

2

rails of said tilted sash. When the second sash is so lowered air may pass over the top of the lowered sash.

Other objects, advantages, and meritorious features will more fully appear in the following drawings, specification and claims wherein:

Fig. 1 is a front elevation from the outside of a permanent window opening with the conventional double hung sashes removed and the window frame and sash assembly of this invention installed;

Fig. 2 is a rear view elevation of the permanent window opening with my window frame and sash assembly installed, as would be seen from inside the building;

Fig. 3 is a cross-sectional view of the frame and sash assembly taken on line 3—3 of Fig. 2;

Fig. 4 is a cross-sectional view taken on line 4—4 of Fig. 2;

Fig. 5 is a broken enlarged cross-sectional view taken on line 5—5 of Fig. 2;

Fig. 6 is an enlarged cross-sectional detail view of the lower jamb face and sash retaining catch taken on line 6—6 of Fig. 4;

Fig. 7 is a schematic cross-sectional side elevation of the frame and sash assembly with the sashes positioned such that air may enter the room, as shown by the arrow;

Fig. 8 is an exploded schematic view of the permanent window opening, the window frame, and the trim panel;

Fig. 9 is a cross-sectional view of the upper pair of sash guide channels taken on line 9—9 of Fig. 8;

Fig. 10 is a cross-sectional view taken through the sash retaining catch perforations in the bottom wall of the lower sash guide channel on line 10—10 of Fig. 8; and

Fig. 11 is a schematic cross-sectional side elevation of the frame with the sashes in a position to admit air, as shown by the arrow.

The permanent window opening of a building, as shown in the figures of the drawings, is formed of a header 20, a sill 21, and opposed jamb members 22. It is here shown as provided with a rectangular trim panel comprising side members 23, a stool member 24, and a header member 26. This trim panel may be either an integral unit or may be secured within the permanent window opening piece by piece. The permanent window opening is also provided with a weather stop formed of side members 28, and a weather stop header member 30. Frequently a window stop (not shown) is mounted upon the jamb faces of the window opening between the weather stop and the trim panel, especially when the window opening is provided with the conventional double hung sashes.

This invention provides a rectangular frame formed of sheet or extruded metal and housing two or three sashes, which is adapted to be secured in a permanent window opening replacing the conventional double hung sashes. It will, of course, be understood that the frame and sash assembly may be used in any window opening provided, as above described, with a weather stop and trim panel.

Said rectangular frame is formed of header member 32, opposed jamb members 34, and a sill member 36. The header comprises a U-shaped channel member the legs of which are folded upon themselves inwardly as at 38 and 40, shown in Fig. 5. A second U-shaped channel 42 of substantially one-half the width of the first channel, and having one leg folded upon itself as at 44, is mounted within the first channel, with one leg 45 telescoped within fold 40 of the first channel. The first and second channels thereby cooperatively form two downwardly opening sash receiving header channels.

The sill member 36, shaped as shown in Fig. 5, is provided with an inner folded leg 46 adapted to abut stool 24 of the trim panel. The sill is further provided with an inner sill channel bottom wall 47, an upstanding intermediate lip 48 formed by a fold of the sill member, an

outer sill channel bottom wall 49, and a folded leg portion 50 adapted to abut the weather stop side members 28 and the permanent sill 21 of the window opening.

Opposed jamb members 34 are channel-shaped, as shown in Figs. 3, 4, 9 and 10. Each of said members is bent to form an inner leg 52 folded upon itself and spaced from a second leg 60, folded upon itself as at 62, by a jamb member bottom wall 58. Each jamb member is further bent to form an extension 66 of leg 62, which extension is folded upon itself, as shown, and is co-extensive with the height of the jamb members, and is adapted to form an exterior wall for the sash guide channels hereinafter described.

Inner and outer upper sash guide channels are formed cooperatively with said jamb members 34 in the following manner. An inner wall 54 is telescopically received within the upper half of the frame within the folded leg 52. Said wall is folded upon itself at its free edge 56 to form a bearing surface for a sash slidably mounted in the upper inner sash guide channel.

An intermediate wall 64, generally Z-shaped in cross section, having a leg portion 68 telescopically received within folded leg 62 of the jamb members, is mounted in the upper half of the frame between exterior wall 66 and inner wall 54. A body portion 70 spaces leg 68 from folded leg 72 and approaches the jamb member bottom wall at an acute angle. This inclination of body portion 70 of the intermediate wall provides a yieldable spring tensioned bearing surface for a sash mounted in the upper outer sash guide channel, tending to hold said sash in selected raised positions.

The lower half of each jamb member 34, as shown in Fig. 10, is provided with a generally L-shaped sash gripping strip 74 having one leg 76 telescopically received within folded leg 52 of the jamb member and the other leg overlying the bottom wall 58 of the jamb member. Said second mentioned leg of the sash gripping strip is bent toward bottom wall 58 as at 78 yieldably spacing the strip from said bottom wall and adapted to hold a sash mounted in the lower half of the frame in selected raised positions. Sash gripping strip 74 and bottom wall 58 of the jamb members are perforated as at 80 and 82 for reasons hereinafter set forth.

The lower and upper sashes of the assembly indicated as A and B respectively in the figures may be formed either of wood or metal construction and overlap at their meeting rails, as shown in Fig. 5. They are of a vertical dimension such that sash B may be raised in the upper outer sash guide channel a distance sufficient to allow sash A to be raised to permit its bottom rail 83 to pass inwardly over lip 48 of the sill member. Sash A is provided on the interior side of each side rail with a sash catch, as shown in Figs. 2 and 6. This sash catch is formed by a generally L-shaped arm 84 pivotally mounted on hinge pin 86 fastened to the side rail 88 of the sash. The catch is adapted to be swung to move the free end of arm 84 selectively into perforations 80 and 82 heretofore described.

To install the window assembly frame within the permanent window opening, the trim panel, double hung sashes, and the window stop are removed and replaced by the frame. The trim panel is then replaced and secured to the sill, header and jamb members of the permanent window opening, thereby holding the said window assembly frame between the weather stop and the trim panel without any other fastening means.

The sashes are successively mounted in the frame through the lower half of the frame. They may be mounted, as shown in Figs. 5 and 11, by slidable movement. Sash A may be locked in the position shown in Fig. 5 by swinging arm 84 from the dotted position, shown in Fig. 6, to the lock position wherein the arm is inserted in perforation 82 of the jamb members. With the lower sash so locked the upper sash cannot be lowered. Lip

48 of the frame sill member serves to prevent inward movement of the bottom rail 83 of the sash.

Fig. 7 shows the sashes mounted to permit air to pass over the upper sash and yet prevent any unauthorized person from entering the room from outside the building. With the sashes in the position shown in Fig. 5, to arrange the sashes as shown in Fig. 7, sash A is moved within the frame so that its bottom rail rests between lip 36 and inner wall 46 of the sill. In this position the 10 sash may be inclined so that its top rail passes under the lower edge of inner wall 54 of the upper inner guide channel. Without completely removing the sash from the frame the sash is then slightly elevated and positioned so that the bottom rail is seated on bottom wall 49 of the sill. The upper meeting rail 85 of sash A is then 15 moved toward the frame until lip 86 engages the lower edge of the upper inner sash guide channel wall 54. The sash catches are swung so that the arms 84 enter perforations 80 in the jamb members. Sash A is then 20 locked in position. Sash B is lowered until its meeting rail rests against the exterior faces of the side rails of sash A, all as shown in Fig. 7.

To perform the above described operations of inserting the sashes within the frame, or positioning them 25 therein so that the lower sash is inclined inwardly of the frame with its meeting rail overlapping the lower ends of the inner wall 54, it will be noted that the dimension between the bottom wall 49 of the sill member and the lower end of the inner wall 54, is less than that of the vertical dimension of the lower sash from the top of its lip 86 to the under face of its bottom rail 83. It will be further noted that the dimension from bottom wall 47 to the lower end of inner wall 54 is greater than the above described vertical dimension of the lower sash.

Three general positions of the sashes within the frame 30 are therefore evident from the drawings and description, namely; where both sashes are in the closed position, as shown in Fig. 5; where the upper sash is completely elevated and the lower sash partially elevated, as shown in Fig. 11; where the lower sash is tilted inwardly of the window opening and the upper sash lowered to rest against the exterior faces of the side rails of said lower sash.

What I claim is:

1. A window frame and sash assembly comprising, in 45 combination, a header member, a sill member, opposed complementary jamb members, said sill member exhibiting an inner upwardly opening sash receiving channel and an outwardly adjacent downwardly opening channel whose bottom wall is spaced above the plane of the bottom wall of said first mentioned channel forming a shoulder adapted to serve as a seat for a window sash slidably supported between said jamb members, said sill member further exhibiting an upstanding ledge disposed between the sill channel and the shoulder and projecting above 50 the sash seating surface of the shoulder and adapted to prevent inward lateral movement of the lower rail of a sash seated on the shoulder.

2. A window frame and sash assembly comprising, 55 in combination, a header member, a sill member, opposed complementary jamb members, a sash slidably mounted in the frame between the jamb members, said sill member exhibiting an inner upwardly opening sash receiving channel and an adjacent exterior downwardly opening channel whose bottom wall is spaced above the plane of the bottom wall of said first mentioned channel, the bottom wall of said second mentioned channel adapted to serve as a seat for said sash slidably supported between said jamb members, each of said jamb members 60 exhibiting upper adjacent inner and outer sash guide channels having an intermediate wall therebetween, said intermediate wall extending downwardly from said header member and having its lower end spaced above the bottom wall of said downwardly opening channel a distance 65 greater than the vertical dimension of said sash, the in-

ner wall of said inner upper sash guide channel extending downwardly from said header member and having its lower end spaced angularly above the bottom wall of said downwardly opening channel a distance such that when said sash is mounted within the frame with its bottom rail abutting the said bottom wall of the downwardly opening channel the meeting rail of the sash will overlap the lower ends of said inner wall.

3. In a window frame assembly; a header portion exhibiting a pair of adjacent downwardly open channels; opposed jamb portions the upper halves of which exhibit a pair of complementary adjacent runway channels defined by inner, outer and intermediate side walls, and the lower halves of which exhibit a single runway 10 extensive in width with the width of the two upper runway channels; and a sill portion exhibiting an upwardly opening channel in line with one channel of the header and an adjacent shoulder offset upwardly from the bottom of said channel in line with the other channel of the header, said shoulder separated from its adjacent channel by a vertical ledge projecting above the shoulder.

4. A window frame and sash assembly comprising, in combination; a vertically slideable sash mounted in the frame; a header member; a sill member shaped to define an upwardly opening channel the outer side wall of which is folded upon itself to exhibit a shoulder extending outwardly laterally away from the channel spaced above the plane of the bottom wall thereof with the bottom wall of said channel and the shoulder adapted to serve as sill seats for said sash; opposed complementary jamb members extending from the header to the sill and each provided with an outer flange projecting toward the opposed jamb member and forming a side wall for a sash guide runway; each jamb member also provided with an inner flange projecting toward the opposed jamb member and extending downwardly from the header with its lower end spaced above the bottom wall of the sill channel a distance greater than the vertical dimension of the sash, and with the lower ends of the inner flanges spaced above said shoulder a distance less than the vertical dimension of the sash, such that when the sash is inclined upwardly and inwardly within the lower half of the frame with its bottom rail seated on said sill shoulder the meeting rail of the sash will abut and underlie the lower ends of said inner flanges.

5. In a window frame jamb assembly comprising: a jamb member shaped in cross section to define an outwardly opening channel with the outside face of the bottom wall of the channel forming a jamb face for the window frame, said channel having a portion folded upon itself to define a lip receiving channel opening inwardly of the jamb face and in a direction opposite the opening of the first mentioned channel; a side wall of one of said channels extending inwardly beyond the jamb face forming a side wall of a sash guide runway; and a runway element overlying the jamb face and cooperating with said side wall of one of the channels to form a sash guide runway, with the element exhibiting a lip portion telescopically received within the lip receiving channel to support and position the element on the jamb face.

6. In a window frame jamb assembly comprising: a jamb member shaped in cross section to define an outwardly opening channel with the outside face of the bottom wall of the channel forming a jamb face for the window frame; each of the side walls of said channel folded upon themselves to define a pair of channels with at least one of the channels opening toward the jamb face, one side wall of one of the said pair of channels projecting inwardly and beyond the jamb face and forming a side wall of a sash guide runway; a runway element exhibiting a lip portion telescopically grippingly received within one channel of said pair with the element overlying the jamb face and cooperating with said sash guide runway side wall to form a sash guide runway.

7. In a window frame jamb assembly comprising: a 75

jamb member shaped in cross section to define an outwardly opening channel with the outside face of the bottom wall of the channel forming a jamb face for the window frame; one side wall of said channel folded upon itself to define a lip receiving channel opening toward said jamb face, with a side wall of the lip receiving channel projecting inwardly of the jamb face and forming a sash guide runway side wall; a runway element exhibiting a lip portion telescopically grippingly received within the lip receiving channel with the element overlying the jamb face and cooperating with said sash guide runway side wall to form a sash guide runway.

8. In a window frame jamb assembly comprising: a jamb member shaped in cross section to define an outwardly opening channel with the outside face of the bottom wall of the channel forming a jamb face for the window frame; each of the side walls of said channel folded upon themselves to define a pair of lip receiving channels opening toward the jamb faces, one side wall of one of the lip receiving channels projecting inwardly and beyond the jamb face and forming a side wall of a sash guide runway; a runway element exhibiting a lip portion telescopically grippingly received within one channel of said pair with the element overlying the jamb face and cooperating with said sash guide runway side wall to form a sash guide runway; and a sash runway side wall telescopically grippingly received within the other lip receiving channel and cooperating with the runway element to form another sash guide runway.

9. In a window frame jamb assembly comprising: a jamb member shaped in cross section to define an outwardly opening channel with the outside face of the bottom wall of the channel forming a jamb face for the window frame; said channel having a portion folded upon itself to define a lip receiving channel opening inwardly of the jamb face and in a direction opposite the opening of the first mentioned channel; a side wall of one of said channels extending inwardly beyond the jamb face forming a side wall of a sash guide runway; a slideable sash overlying the jamb face; and a sash engaging element provided with a lip portion grippingly telescopically received within the lip receiving channel and provided with another portion tensioned inwardly away from the jamb face and toward the sash and adapted to yieldingly hold the sash in selected elevated positions.

10. In a window frame jamb assembly comprising: a jamb member shaped in cross section to define an outwardly opening channel with the outside face of the bottom wall of the channel forming a jamb face for the window frame; one side wall of the channel folded upon itself to define a flange projecting inwardly of the jamb face and forming a side wall of a sash guide runway; the other side wall of the channel folded upon itself to form a lip receiving channel opening inwardly of the jamb face; a slideable sash mounted in the frame and overlying the jamb face; and a sash engaging element provided with a lip portion grippingly telescopically received within the lip receiving channel and provided with another portion overlying the jamb face and disposed between the jamb face and the sash and extending toward the flange, with the second portion tensioned inwardly away from the jamb face and against the sash to hold the sash in selected elevated positions.
